UNITED STATES PATENT OFFICE.

JASON KETH JONES, OF TOPEKA, KANSAS.

DESIGN FOR A PUTTY-KNIFE.

SPECIFICATION forming part of Design No. 32,229, dated February 13, 1900.

Application filed December 11, 1899. Serial No. 740,011. Term of patent 7 years.

To all whom it may concern:

Be it known that I, JASON KETH JONES, a citizen of the United States, residing at Topeka, in the county of Shawnee and State of Kansas, have invented a certain new and useful Design for a Putty-Knife; and I do declare the following to be a full, clear, and exact description of the invention, such as will enable others skilled in the art to which it appertains to make and use the same.

My invention relates to a new and useful design for a putty-knife, and the figure in the drawing is a perspective view of the putty-knife, which is the subject of my invention.

The essential feature of my design is a T-shaped tool or implement, the shank of which is cylindrical and its free end terminates in a V-shaped putty-blade, while the cross-bar

is flattened on its outer end at the point of meeting with the right-angular arm of the shank. This cross-bar lies at an acute angle to the shank-arm, and its free end terminates in the flattened blade, as shown.

Having thus fully described my invention, what I claim as new and useful, and desire to secure by Letters Patent of the United States, is—

The design for a putty-knife, substantially as herein shown and described.

In testimony whereof I have hereunto set my hand in presence of two subscribing witnesses.

JASON KETH JONES.
